WILLIAM ADAM SCHOLLMAYER, OF YONKERS, NEW YORK

MILK BOTTLE CLOSURE

Application filed January 10, 1930. Serial No. 419,786.

This invention relates to new and useful improvements in milk bottle closures and its object is to provide a simple arrangement which will effectively cover the top of the bottle when material therein is in liquid condition and which will maintain the covering of the material when it freezes and expands above the top of the bottle.

It is well known that when milk bottles are delivered in climates when the temperature is below the freezing point of the milk, the latter freezes and expands, dislodging the cap from its seat and exposing the protruding part of the milk to dust and dirt. In some communities, ordinances have been passed prohibiting the delivery of milk during early morning hours, in order to overcome this unsanitary condition. I am aware that attempts have been made to provide elastic covers which will protect the protruding milk, but such arrangements have not been satisfactory. I have, however, by the simple expedient herein described, provided an inexpensive sanitary closure which may be easily applied, and which meets all requirements.

Referring to the drawing,

Fig. 1 is a sectional elevation of the neck and top of an ordinary milk bottle with an embodiment of my invention applied thereto;

Fig. 2 is a top plan view of the parts shown in Fig. 1; and

Fig. 3 is a top plan view of the same parts with the outer cover removed.

10 designates a milk bottle of ordinary construction with an annular seat for the reception of a disk 11 below its upper edge 12. The upper end of the bottle is thickened and enlarged as at 13.

My novel closure comprises a paper cap formed as shown in Fig. 1 with a flat top portion 20, annular bellows-like folds 21 and a depending skirt 22. This is placed on the top of the bottle as shown, and the skirt 22 tied in under the enlargement 13 by a string or wire 23. The inside diameter of the folds is preferably larger than the diameter of the disk 11 and its outside diameter is preferably less than that of the enlargement 13.

It may be seen that an expansion of the milk caused by freezing will simply push up the top 20 which upon rising will open the folds 21 without exposing or uncovering that part of the milk which protrudes or extends above the top of the bottle. When the disk 11 is used, this will be interposed between the top of the protruding column of milk and the flat top portion 20 of the cover.

When an outer paper cover such as is shown at 30, is used, I prefer to provide a circular series of perforations 31 therein, outside of the folds 21. This makes the outer cap frangible so that it will not be pulled out of the cord or wire 23 which in this case holds both the cover and the outer cap on the bottle.

Having thus described my invention, what I claim is:

1. A milk receptacle comprising a bottle having an opening at the top thereof, an enlarged neck flange surrounding said opening, a paper closure having a flat portion adapted to extend over the opening of the bottle, a skirt adapted to extend downwardly around the neck of the bottle and to be secured thereto, and a plurality of folds forming an annular expansible intermediate portion combined with a cap having a flat portion extending over and in contact with the flat portion of said closure, a skirt extending over and in contact with the skirt of said closure and a cylindrical side of larger diameter than that of said folds lying against the neck of the bottle constructed with circularly arranged perforations surrounding the flat portion of said inner closure.

2. A milk receptacle comprising a bottle having an opening at the top thereof, an internal annular shoulder, a disk thereon, an enlarged neck flange surrounding said opening, a paper closure having a flat portion adapted to extend over the opening of the bottle, a skirt adapted to extend downwardly around the neck of the bottle and to be secured thereto, a plurality of folds forming an annular expansible intermediate portion combined with a cap having a flat portion extending over and in contact with the flat portion of said closure, a skirt extending over

and in contact with the skirt of said closure
and a cylindrical side of larger diameter
than that of said folds lying against the neck
of the bottle constructed with circularly ar-
ranged perforations surrounding the flat por-
tion of said inner closure, and means for se-
curing the outer paper cover and the skirt
of said closure to the bottle below its flange.
